UNITED STATES PATENT OFFICE.

HOWARD PARKER, OF BERLIN, NEW HAMPSHIRE, ASSIGNOR TO BROWN COMPANY, OF BERLIN, NEW HAMPSHIRE, A CORPORATION OF MAINE.

REPAIR ELEMENT FOR FIBROUS CONDUITS.

Application filed July 14, 1925. Serial No. 43,600.

This invention relates to repair elements or members for conduits, and is more particularly concerned with members made of fibrous material and adapted for use in connection with cylindrical conduits made of the same material.

Such conduits or tubes may be formed by winding a web of cellulose pulp or a sheet of paper on a mandrel until a tube having a wall of the desired thickness has been formed, then removing the tube from the mandrel and thoroughly drying it. When used as a conduit or closure for electric wiring or as a water pipe, the tube may be waterproofed and rendered electro-insulating by impregnating or saturating it with pitch or other suitable material.

When such conduits are employed in practice as in electric wiring systems, it frequently occurs that a conduit is broken at some point in the system. Since such systems are usually buried in the ground or located in tiled trench, it would ordinarily be necessary to disconnect and remove the broken conduit unit from the system and replace the removed conduit by a new one. Such procedure is obviously time consuming and expensive. Hence the primary object of the present invention is to provide a repair element which may be employed in repairing a broken fibrous conduit in an efficient manner and without the necessity for the removal of the broken conduit from the system.

This object is attained in a repair element which may for convenience of designation be termed a "snap repair element." The element in general consists of a longitudinal cylindrical conduit section, of an inside diameter equal to the outside diameter of the conduit to be repaired, over which it may be snapped at its broken portion.

On the accompanying drawings, which together with the following description give a more complete understanding of the present invention,

Figure 1 illustrates in perspective a repair element or member snapped over the wall of a broken conduit.

Figure 2 represents a section along the line 2-2 of Figure 1.

Referring to the drawings, 1 illustrates a conduit of indefinite length having a break therein, illustrated by the ragged hole at 2. In repairing the break, molten asphalt, cement, or other suitable binder is applied to

the outer surface of the wall adjacent to or neighboring the break, and a repair member represented at 3 and preferably also coated on its inner surface with binder material is snapped or forced over the broken conduit. 60 Binder may also be applied at the edges of the repair member or entirely around the conduit to ensure a perfect moisture proof seal after the setting thereof.

The member 3, as shown, consists of a longitudinal conduit section, the arc of a transverse section of which is more than 180°, and the inside diameter of which is equal to the outside diameter of the conduit undergoing repair. By the use of such construction, I 70 have discovered that the repair member may be forced over the broken conduit so that its bowed or converging extremities embrace the conduit and ensure the union therebetween without the use of other uniting means such as 75 wires or straps. The repair may be made without the necessity for the disconnection of the broken conduit from the system, and the repair member or element tightly and effectively seals the wall of the conduit. 80

Members formed of fibrous material as herein described are rigid, and waterproof, if desired, and possess a certain modulus of elasticity. Its longitudinal edges 4 and 5 are separated a sufficient distance, so that it 85 exerts a spring action on the repaired conduit to maintain it in its snapped position, but without being permanently deformed or cracked.

Having thus described an embodiment of 90 this invention, it should be evident that it is capable of various changes and modifications without departing from its spirit as defined by the appended claims.

What I claim is:

1. A fibrous repair element for use in connection with a cylindrical conduit of like fibrous material, which comprises a section of conduit of cylindrical form having an inside diameter substantially equal to the outside diameter of the conduit undergoing repair and having resilient walls of comparatively great rigidity extending through an arc of more than 180°, said repair element being adapted to be snapped over the outer 100 surface of the conduit to be repaired and to remain in place by its inherent resilience.

2. A fibrous repair element for use in repairing cylindrical conduits made of like fibrous material, said element comprising a 110

conduit section having a wall of comparative-
ly great rigidity which in cross section forms
an arc of more than 180° , the longitudinal
edges of said element being capable of being
sprung apart a sufficient distance to permit
said edges to be snapped over the fibrous con-
duit to be repaired without said element being

permanently deformed or cracked, said ele-
ment having sufficient inherent resilience to
remain in conduit embracing position.

10

In testimony whereof I have affixed my sig-
nature.

HOWARD PARKER.
